[57] CLAIM

The ornamental design for a disposable absorbent baby bib, as shown and described.

DESCRIPTION

FIG. 1 is a front elevational view of the disposable absorbent baby bib showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof, shown in use, the broken lines showing an infant being for illustrative purposes only.

The broken lines shown on the bib in FIGS. 1, 2, and 7 are understood to represent conventional stitching.

FIG. 1

FIG. 2

*FIG. 3**FIG. 4**FIG. 5*

FIG. 6

FIG. 7
